UNITED STATES PATENT OFFICE.

JAMES P. FISHER, OF BARTLESVILLE, OKLAHOMA, ASSIGNOR, BY MESNE ASSIGNMENTS, TO DOHERTY RESEARCH COMPANY, OF NEW YORK, N. Y., A CORPORATION OF DELAWARE.

DEMAND-LIMITING DEVICE.

Application filed August 29, 1919. Serial No. 320,586.

To all whom it may concern:

Be it known that I, JAMES P. FISHER, residing at Bartlesville, in the county of Washington, State of Oklahoma, have invented certain new and useful Improvements in Demand-Limiting Devices; and I do hereby declare the following to be a full, clear, and exact description of the invention, such as will enable others skilled in the art to which it appertains to make and use the same.

This invention relates to a demand limiting device for limiting the quantity of fluid which may be withdrawn from a fluid supply line in any given unit of time.

In the distribution of fluids such as natural or artificial gas in which the consumption is subject to seasonal and hourly variations, the demand may at times exceed the available supply if no limit is placed on the customers' consumption. During periods of excessive demand, those consumers situated nearest the source of supply and therefore drawing their gas from sections 25 of the mains having the highest pressure are able to obtain more than their proportionate share of the available supply, with the result that consumers less fortunately situated may not be able to obtain an amount of gas equal to their normal needs. In order to obtain an equitable distribution and equality of service to all consumers, it is therefore necessary to limit the amount of gas which may be used by each consumer, regardless of the pressure in the mains, to a definite maximum proportioned to each consumer's normal gas consumption. By limiting the maximum demand of each consumer, which limit may be fixed by a 40 service charge, the gas supply company will be able at all times to supply gas to each consumer up to the limit of demand. In this way, it will also be possible to obtain a more uniform pressure in all sections 45 of the supply mains. In limiting the supply to each consumer, it will, of course, be necessary to prevent the possibility of the demand limit being changed by the consumer and to avoid any interference with or 50 irregularity in the normal supply of gas.

The object of the present invention is to provide a demand limiting device of simple and compact construction for limiting the rate of passage of fluid regardless of the supply pressure.

Another object of the invention is to provide a demand limiting device of simple construction which may be easily mounted in any of the commonly used gas service piping systems.

Another object of the invention is to provide a demand limiting device in which the limit can not be changed without changing parts of the apparatus, whereby each consumer is enabled to obtain only the amount 65 of gas contracted for by him.

With these and other objects in view, the invention consists in the fluid limiting device described in the following specification and defined in the claims.

The various features of the invention are shown in the accompanying drawing, in which,

Figure 1 is a vertical sectional elevation taken on line 1—1 of Fig. 2, of a demand 75 limiting device embodying a preferred form of the invention;

Fig. 2 is a horizontal section of the demand limiting device on line 2—2 of Fig. 1;

Fig. 3 is a horizontal section of the demand limiting device on line 3—3 of Fig. 1; and

Fig. 4 is a detail view of the valve forming part of the demand limiting device.

In the demand limiting device of the present invention a uniform quantity of gas is admitted to the service line through a valve controlled by a standard orifice disk. The gas is passed through the standard orifice disk under a difference in pressure which 85 differential is prevented from rising above a definite maximum. The quantity of gas flowing through an orifice will depend upon the size of the orifice and the difference in pressure of the gas on opposite sides of the orifice disk. The size and number of the orifices for any given demand will be fixed 90 and will be proportioned to the maximum quantity of gas to be supplied. The valve which is controlled by the disk is so ar-

anged that when the difference in pressure on opposite sides of the disk corresponds with the normal passage of gas, the weight of the valve and disk will hold the valve in wide open position. As the flow of gas and consequently the difference in pressure on opposite sides of the disk increases to the demand limit, the valve is raised by the disk into a partially closed position to throttle the gas passing to the orifices and thereby 105 110

hold the pressure differential through the orifices within the fixed limit.

In the embodiment of the invention shown in the accompanying drawing, gas from the service main, after passing through a meter, enters the bottom of an L-shaped coupling 10 of the demand limiting device through a union nipple 12. The gas passing through the nipple 12 enters a chamber 14 formed in the lower part of the casing 10 by a flange 16 projecting inwardly from a valve casing 18 and a circular plate 20 rigidly supported above the flange 16 by spiders 22 extending to the walls of the valve casing 18. The flange 16 is formed with an opening 24, and a cylindrical valve cage is formed in the casing 18 by the wall of the opening 24 and a downwardly extending cylindrical flange 28 on the plate 20. A port 26 is provided in the valve cage between the cylindrical opening 24 and the lower edge of the flange 28. The opening 24 and the inner surface of the flange 28 are on the same cylindrical surface and a cylindrical valve 30 works in this cylindrical cage across the port 26. After the gas passes through the port 26, it flows upwardly within the walls of the valve casing 18 to an orifice disk 32 which extends across the path of the gas and loosely contacts with the walls of the valve casing 18. The orifice disk does not form a tight contact with the valve casing 18 but leaves a small space between the edge of the disk and the wall of the casing through which a small part of the gas leaks upwardly. The greater part of the gas, however, passes under a difference in pressure through orifices 34, Fig. 2, in the orifice disk 32 to the upper part of the casing 10 from which it flows into the domestic piping line through an outlet 36. The difference or drop in pressure on opposite sides of the disk 32 created by the passage of gas through the orifices 34 tends to lift the disk upwardly through the valve casing 18. The disk 32 is normally prevented from rising, by the weight of the valve 30 to which it is connected by a spindle 38 passing loosely through the plate 20 and rigidly fastened at its ends to the disk 32 and the valve 30. When the rate of flow of gas through the coupling 10 is below the demand limit, the weight of the valve 30 and orifice disk 32 will overcome the lifting effect of the gas passing upwardly through the orifices 24, and the orifice disk will sink to its lowest position and rest on the boss 40 upstanding from the plate 20. In as much as the disk 32 makes only point contacts with the boss 40, there is no tendency for it to adhere to the plate 20, if tar or oil collects in the casing. As the rate of flow tends to become slightly greater than the demand limit, the lifting effect of the flowing gas will overbalance the weight of the disk 32 and valve 30 and raise the valve 30 to close

the port 26 leading from the chamber 14. The action of the valve thus throttles the passage of gas through the port 26 and brings the rate of flow back to the limiting value.

Inasmuch as the orifice disk 32 is disposed across the path of flow of the gas through the device, it is subjected to a force arising from the impact of the gas on the disk as well as to the force resulting from the difference in pressure on opposite sides of the disk. Moreover, when the flow of gas through the device and the pressure differential across the disk are increased, the velocity of the gas and the force of the impact of the gas on the disk are also increased. When the flow of the gas exceeds a certain limit, the force due to the velocity of the gas becomes so great in proportion to the force of the differential across the disk that the operation of the device is rendered inaccurate. Consequently, the kinetic energy of the gas imposes a limit on the capacity of a demand limiting device in which the valve controlling element is located in the path of flow of the gas.

It is found that when a fluid flowing under confinement is deflected sharply in its course, as, for example, by passing through an abrupt right-angle elbow, a considerable decrease in pressure takes place. In the illustrated construction, the arrangement of the plate 20 and its flange 28 with relation to the valve 30, valve casing 18, and orifice disk 32 is such that the gas after passing through the port 26 under the control of the valve 30 is compelled to turn at right angles before passing on to the orifice disk 32. Consequently, the pressure of the gas is considerably reduced in passing through the valve casing 18, thus reducing the velocity with which the gas impinges on the orifice disk 32. In this manner the plate 20 and flange 28 act to reduce the force of the impact of the gas on the orifice disk and thereby increase the capacity of the device.

In order not to interfere with the pressure at which the gas is supplied to the consumer, the orifices 34 should be of such a size that the difference in pressure on opposite sides of the disk 32 will be very small. Accordingly, the force acting to close the valve 30 when the pressure difference on the orifice disk rises by a very slight amount over that corresponding to the demand limit is very small. To enable this small force to promptly operate the valve 30, the orifice disk 32 is fitted to move without friction over the walls of the valve casing 18, in which it is guided. In order to obtain a freely movable frictionless contact between the edge of the orifice disk 32 and the cylindrical walls of the valve casing 18, the outer edge of the orifice disk is curved downwardly and bent inwardly to present a curved surface to the

casing 18. By this means, a comparatively close contact of considerable breadth is formed between the edge of the disk 32 and valve casing 18, while at the same time any 5 wedging action due to a slight tilting of the disk 32 is prevented by the rounded edge formed on the flange 42.

Friction between the valve 30 and the edge of the opening 24 in the flange 16 is 10 also prevented by making the valve 30 a little smaller than the opening 24 to give considerable clearance between the valve and the edge of the opening. A leakage through this clearance is of no great disadvantage 15 since a certain passage for gas should always be left between the chamber 14 and the interior of the valve casing 18. However, when a valve having a straight upper edge is used, there is a tendency, for the valve to 20 become unbalanced due to the high velocity of the gas across its upper edge. To avoid this and the consequent danger of wedging the valve, a number of notches 44 are cut in the upper edge of the valve 30 through 25 which the gas may escape in a regular manner as the upper edge of the valve 30 moves into the rim 28 of the valve plate 20. The notches 44 consist of an upright abutment face 46, an inclined face 48 extending from 30 the valve edge to the bottom of the face 46 and an inclined face 50 extending from the valve edge to the top of the face 46. By using an annular valve, the pressure of the 35 gas on one side of the valve is just balanced by the pressure on the other side. With this construction, the valve will not be held in closed position by the gas pressure as would be the case if an unbalanced valve were used.

The quantity of gas which may pass 40 through the demand limiting device will depend upon the size and number of the orifices 34 and the combined weight of the valve 30 disk 32 and spindle 38. When the device is once installed, therefore, the demand limit cannot be changed or adjusted 45 without changing the disk 32. To permit this adjustment to be made, the coupling 10 is provided with a union nut 52 in its lower part in which the nipple 12 is threaded and 50 through which access may be had to the interior of the device. The valve casing 18 is supported in the coupling 10 by means of an outwardly extending flange 54 clamped between the upper edge of the nut 52 and a 55 ledge 56 formed on the coupling 10. Gaskets 58 are provided on each side of the flange 54 to insure a gas-tight joint. On removing the nut 52, the valve casing 18 may be removed from the coupling 10 and access had 60 to all parts of the apparatus.

In some cases where the demand limit is low or when the gas pressure is high the distance between the periphery of the disk 32 and the inner wall of the casing 18 may be 65 calibrated to permit all of the gas to pass

around the periphery of the disk. With this construction no orifices 34 will be placed in the disk 32.

With the demand limiting device in the form of an elbow coupling, the device may 70 be used in the place of an ordinary elbow and union nipple in a service pipe connection with a meter. The threaded outlet 36 and the union nipple 12 serve as a means by 75 which the device may be connected into the service line quickly without other alteration of piping.

The preferred form of the invention having been thus described what is claimed as new is:

1. In a fluid demand limiting device, the combination of a valve casing, a valve in the said casing, a disk connected to said valve and mounted to be freely movable along the inner wall of the casing so as to permit a 80 limited flow of fluid between the edge of the disk and the casing wall, and means for decreasing the pressure of fluid passing through the casing between the valve and the disk. 90

2. In a fluid demand limiting device, the combination of a valve casing, an annular valve in said casing, an annular member normally spaced from the upper edge of the valve, notches on the upper edge of the 95 valve, and a disk mounted in said casing and operable to move the valve toward and from the annular member.

3. In a fluid demand limiting device, the combination of a valve casing, a hollow 100 valve in said casing, notches on the upper edge of said valve, a member shaped correspondingly to the valve and normally spaced from the upper edge of the valve, and an orifice disk slidably mounted in the casing 105 and operable to move the valve toward and from said member.

4. In a fluid demand limiting device, the combination of a valve casing, a disk slidably mounted in said casing, a hollow valve 110 mounted in the casing and provided with notches on its upper edge, said notches comprising an upright abutment face and inclined faces at each side of said upright face, a member mounted in the casing above the valve, and connections between the disk and the valve for moving the valve forward and from said member. 115

5. A fluid demand limiting device comprising a valve casing having a substantially 120 vertical cylindrical wall and a horizontal flange projecting inwardly from the wall, a valve slidably contacting with the inner edge of said flange, a spindle connected with the valve, an orifice disk rigidly fastened 125 to the upper edge of the spindle and mounted to slide in the valve casing, and a plate interposed between the valve and the orifice disk and constructed and arranged to cause the fluid current to be sharply deflected 130

in passing from the valve to the orifice disk so as to decrease the pressure of the fluid during its passage from the valve to the disk.

6. A fluid demand limiting device comprising a valve casing, a hollow valve movable in a direction substantially parallel to the walls of the casing, an orifice disk movable in the valve casing, a spindle for connecting the orifice disk to the valve, and a plate co-acting with the valve between the valve and the orifice disk and constructed to cause the fluid current to be deflected at substantially right angles in passing from the valve to the disk so as to decrease the pressure of the fluid during its passage from the valve to the disk.

7. In a fluid demand limiting device, the combination of an orifice disk in the path of the fluid and a hollow annular valve operated by said disk and constructed so as to cause the gaseous pressures on the valve to be balanced in all positions of the valve.

8. In a fluid demand limiting device, the combination of a freely movable disk, a cylindrical chamber closed at one end, a port in the cylindrical wall of said chamber for the passage of fluid to said disk, and a freely movable slide valve actuated by said disk to move over said port.

9. In a fluid demand limiting device, the combination of a freely movable disk, a cylindrical chamber closed at one end, a port in the cylindrical wall of said chamber for the passage of fluid to said disk, and a freely movable annular slide valve actuated by said disk to move over said port.

10. In a fluid demand limiting device, the combination of a freely movable disk, a cylindrical chamber closed at one end, a port in the cylindrical wall of said chamber for the passage of fluid to said disk, and a freely movable balanced slide valve actuated by said disk to move over said port.

11. In a fluid demand limiting device, the combination of a freely movable orifice disk, a cylindrical chamber closed at one end, a port in its cylindrical wall for the passage of fluid to said disk, an annular slide valve movable over said port, and means for rigidly connecting said valve and said disk.

12. A demand limiting device, comprising a valve casing having an inwardly extending flange, a valve plate spaced a short distance above said flange, a valve movably mounted in an opening in said flange and arranged for closing the space between said flange and said valve plate, a spindle extending from said valve through said valve plate, and an

orifice disk rigidly attached to said spindle and slidably contacting with the walls of said casing.

13. A demand limiting device, comprising a valve casing, a valve cage mounted in said casing having a substantially vertical cylindrical wall, a valve plate arranged to close the upper end of said cage, ports in said cage, an annular valve arranged to move across said ports, notches in the upper edge of said valve, a spindle connected to said valve and extending through said valve plate, and a movable orifice disk rigidly fastened to the upper end of said spindle and slidably contacting with the walls of said valve casing.

14. In a fluid demand limiting device, the combination of a valve casing, a valve cage in the casing comprising a cylindrical member closed at its upper end and having its periphery spaced from the wall of the casing, an orifice disk above the cylindrical member, a valve mounted for movement in the valve cage and adapted to be received in the cylindrical member, and connections between the orifice disk and the valve for moving the valve toward and from the cylindrical member, the arrangement of the valve, the cylindrical member, the valve casing, and the orifice disk being such that the fluid current is deflected substantially at right angles during its passage from the valve to the orifice disk so as to decrease the pressure of the fluid during its passage from the valve to the disk.

15. A demand limiting device comprising, an L-shaped coupling threaded at its openings, a valve casing secured within one opening of said coupling by means of a union nut, a valve cage in the casing, a union nipple mounted in said nut, a port in said cage, a valve in said cage arranged to open and close said port, and a disk connected with said valve and slidably mounted in the valve casing.

16. A fluid demand limiting device comprising a valve casing, a valve slidably mounted in the casing, an orifice disk connected to the valve, and a member co-acting with the valve to control the passage of fluid through the casing and constructed and arranged with relation to said first-mentioned parts so as to decrease the pressure of the fluid during its passage from the valve to the orifice disk.

In testimony whereof I affix my signature.

JAMES P. FISHER.
